UNITED STATES PATENT OFFICE.

FREDERIC WILLIAM CHAMIER, OF HYDE PARK, LONDON, ENGLAND, ASSIGNOR TO
C. P. G. COMPANY LIMITED, OF LONDON, ENGLAND.

HAND-GRENADE AND THE LIKE.

1,303,164.

Specification of Letters Patent.

Patented May 6, 1919.

Application filed November 27, 1916. Serial No. 133,667.

To all whom it may concern:

Be it known that I, FREDERIC WILLIAM CHAMIER, a subject of the King of Great Britain, residing at 63 Queensborough Terrace, Hyde Park, in the county of London, England, have invented certain new and useful Improvements in or Relating to Hand-Grenades and the like, of which the following is a specification.

10 This invention relates to hand grenades and trench mortar bombs of the kind provided with a pivoted safety lever located externally of the grenade and controlling the firing mechanism.

15 In such devices the pivoted lever is usually held in its inoperative position by a safety pin, which, when withdrawn, permits of the release of the said lever immediately the grenade or bomb (hereinafter termed "grenade") leaves the hand of the thrower or has been discharged from the trench mortar or other throwing device.

20 According to the present invention a weighted member preferably in the form of an arm or lever is detachably connected to the grenade in such manner that after the safety pin has been withdrawn, the safety lever remains held in its inoperative position until after the grenade has been thrown and 25 until a differential movement causes the weighted member to become automatically detached from the grenade.

30 In order that the said invention may be clearly understood and readily carried into effect the same will now be described more fully with reference to the accompanying drawing, which shows the preferred embodiment of the invention and in which:—

35 Figure 1 is a part sectional elevation showing the weighted member or arm applied to a hand grenade of the percussive or impact type, the pivot for the safety lever being located on the left hand side of the grenade.

40 Fig. 2 is an elevation at right angles to Fig. 1.

45 Fig. 3 is a part sectional elevation showing the weighted member or arm applied to a hand grenade fitted with a time fuse the pivot for the safety lever being located on the right hand side of the grenade.

50 Fig. 4 is a view showing the weighted member or arm detached from the grenade.

The said weighted member or arm A comprises in the example shown a strip of spring 55 steel, provided at one extremity with a

weight B, the mass of which is chosen according to the point at which it is desired that the weighted arm shall separate from the grenade after the grenade has been thrown, its other extremity being formed 60 with a clip C constituted by two suitably bent lugs D, D, formed with recesses C' so that the clip C can be snapped into a locking position upon a pin E supported between a pair of lugs F, F formed integral 65 with or carried by the lower part of the grenade. The weighted arm A is adapted to lie against the safety lever G, which is pivoted at I, and to occupy such a position that the weight lies with its axis or center of 70 gravity coincident or substantially coincident with the axis of the grenade, the steel strip of which the arm is formed conforming to the contour of the safety lever G. The pivotal center of the clip C is located 75 slightly below the axis of the pin E, so that on applying the weighted arm A to the grenade, the clip C on the end of the arm will snap into position past the dead center which is thus formed, and the fulcrum of 80 the arm being thus positioned below the axis of the pin E, the clip C will serve normally to hold the said arm in place. When, however, the usual locking pin H is withdrawn and the grenade is thrown and has traveled 85 a certain distance, a differential movement between the arm and the grenade will occur which will cause the weighted arm to turn outward and away from the grenade, until it moves beyond the dead center of the clip 90 connection whereupon the weighted arm will become detached from the grenade and allow the safety lever G to fly outward in the usual manner.

95 It will be apparent that by the provision of this device, the safety lever G is prevented from operating until the grenade has traveled a certain distance after being thrown and that the grenade will not explode before being thrown even if it should accidentally fall or be dropped upon the ground or roll down the steps of a dug out after the removal of the safety pin.

100 What I claim and desire to secure by Letters Patent of the United States is:—

105 1. A grenade comprising firing mechanism, an externally arranged spring controlled safety lever forming part of the firing mechanism, a weighted member normally serving to retain the safety lever in its inoperative

position, and means for detachably connecting said weighted member to the grenade in such manner that after the grenade has been thrown the said weighted member becomes automatically detached during the flight of the grenade and thereby releases the firing mechanism.

2. A grenade comprising firing mechanism, an externally arranged spring controlled safety lever forming part of the firing mechanism, a weighted member normally serving to retain the safety lever in its inoperative position, and means for detachably connecting said weighted member to the grenade in such manner that after the grenade has been thrown, a differential movement arising during the flight of the grenade causes the weighted member to become detached and permits the safety lever to release the firing mechanism.

3. A grenade comprising firing mechanism, an externally arranged spring controlled safety lever forming part of the firing mechanism, a weighted arm or lever normally serving to retain the safety lever in its inoperative position, and means for detachably connecting said weighted arm or lever to the grenade in such manner that after the grenade has been thrown a differential movement arising during the flight of the grenade causes the weighted arm or lever to become detached and permits the safety lever to release the firing mechanism.

4. A grenade comprising firing mechanism, an externally arranged spring controlled safety lever forming part of the firing mechanism, an arm or lever, a weight at one end of said arm or lever and means at the other end of said arm or lever for detachably connecting it to the grenade in such manner that said weighted arm or lever will retain the safety lever in its inoperative position until the grenade has been thrown.

5. A grenade comprising firing mechanism, an externally arranged spring controlled safety lever forming part of the firing mechanism, an arm or lever, a weight at one end of said arm or lever normally lying in a position more or less co-axial with the grenade, and means at the other end of said arm or lever for detachably connecting it to the grenade at a point adjacent to the free end of the safety lever in such manner that said weighted arm or lever will retain

the safety lever in its inoperative position 55 until the grenade has been thrown.

6. A grenade comprising firing mechanism, an externally arranged spring controlled safety lever forming part of the firing mechanism, an arm or lever, a weight 60 at one end of said arm or lever normally lying in a position more or less co-axial with the grenade, and means at the other end of said arm or lever for detachably connecting the latter to a pin on the grenade 65 in such a position that this end of the arm or lever lies adjacent to the free end of the safety lever and at a point below the dead center of the connection, until after the grenade has been thrown.

7. A grenade comprising firing mechanism, an externally arranged spring controlled safety lever forming part of the firing mechanism, an arm or lever, a weight 75 at one end of said arm or lever normally lying in a position more or less co-axial with the grenade, and a clip at the other end of said arm or lever for detachably connecting the latter to a pin on the grenade in such a position that this end of the arm or lever 80 lies adjacent to the free end of the safety lever and at a point below the dead center of the connection, until after the grenade has been thrown.

8. A grenade comprising firing mechanism, 85 an externally arranged spring controlled safety lever forming part of the firing mechanism, a flexible arm or lever conforming more or less to the shape of the safety lever, a weight at one end of said arm or lever normally lying in a position more or 90 less co-axial with the grenade, a clip at the other end of said arm or lever for detachably connecting the latter to a pivot pin on the grenade in such a position that this end of 95 the arm or lever lies adjacent to the free end of the safety lever and at a point below the dead center of the connection, until after the grenade has been thrown.

9. An attachment for a grenade, comprising 100 an arm or lever having at one end a weight and at the other end means for detachably connecting it to the grenade in a position to normally retain the safety lever of the grenade in an inoperative position 105 until the grenade has been thrown.

FREDERIC WILLIAM CHAMIER.
